UNITED STATES PATENT OFFICE.

WILLIAM J. DECKER, OF DETROIT, MICHIGAN.

BOW-REST.

No. 875,052.

Specification of Letters Patent.

Patented Dec. 31, 1907.

Application filed May 17, 1907. Serial No. 374,235.

To all whom it may concern:

Be it known that I, WILLIAM J. DECKER, a citizen of the United States, residing at Detroit, in the county of Wayne and State of Michigan, have invented certain new and useful Improvements in Bow-Rests, of which the following is a specification.

This invention is a bow rest or spacer adapted for use on the tops of automobiles or other vehicles, for the purpose of preventing marring or injury to the bows by rubbing or knocking together incident to the vibration of the vehicle.

The object of the invention is to form a simple and ornamental device for the purpose intended, which will retain the bows in proper alignment and at a fixed distance apart and prevent contact between the bows.

The device is illustrated in the accompanying drawings, in which

Figure 1 is a side view showing parts of a set of bows provided with the invention. Fig. 2 is a section on the line 2—2 of Fig. 1.

In the drawings, 6 indicate the bows. The spacers or rest each comprise a pair of fixtures one of which has the form of a cup as indicated at 7, and the other of which has the form of a stud or lug, as indicated at 8, which fits within the cup. The base of the cup or socket piece is enlarged or flared, and concaved to fit the curvature of the bow. And the base of the stud is similarly formed. These parts are arranged oppositely, one being fixed to one bow and the other to the adjacent bow, so that when the top is let down the studs will enter the cups and rest therein.

The two members of the respective pairs or sets are attached to opposite sides of the bow, by means of a rivet 9, the head of which is

seated in the socket or cup and forms a bottom or floor thereto, and the other end of which is expanded or upset over the end of the stud. By thus riveting the parts together they are very firmly fixed. Obviously a screw may be used instead, if desired, and one rivet or screw serves to attach both of the fixtures to the bow. Any weakening of the bow incident to boring through the same is corrected by the strength afforded by the enlarged or extended bases of the fixtures.

These rests are set in pairs on the bows, and when once fitted they will thereafter strike each other when the vehicle top is lowered. The fit of the stud within the cup is sufficiently close to prevent any lateral vibration of the parts, and inasmuch as the bows are spaced apart the wear incident to rubbing together is avoided. When constructed in brass or other metal, the parts are ornamental in appearance, and do not detract from the looks of the vehicle top.

I claim:

A set of spacers for the bows of a vehicle top, comprising pairs of cup and stud pieces secured to the bows and located therebetween, respective pieces of each pair being attached to opposite sides of the bow by a single fastening device extending through the bow, the studs being located to enter the cups when the top is folded.

In testimony whereof I affix my signature, in presence of two witnesses.

WILLIAM J. DECKER.
